JOHN H. BELLAMY, OF CHARLESTOWN, MASSACHUSETTS, ASSIGNOR TO ELBRIDGE WOLCOTT AND JONAS C. YOUNG, OF SAME PLACE.

Design No. 4,854, dated May 2, 1871.

DESIGN FOR THE FRONT OF A CATCH-ALL.

The Schedule referred to in these Letters Patent and making part of the same

To all whom it may concern:

Be it known that I, JOHN H. BELLAMY, of Charlestown, in the county of Middlesex and State of Massachusetts, have originated and Designed a new and useful Pattern for the Front of a Catch-All, of which the following is a full, clear, and exact description, reference being had to the accompanying photographs and to the letters of reference marked thereon making a part of this specification.

The nature of my invention consists in so arranging emblems as to show above the base A a five-pointed star, B, above which are balls, C, cross-cannons D, sword E, the whole being surmounted by an eagle, F; below star B, and on the right are an anchor, G, flag H, and cross-guns I I; on the left of star B, and below it, are a bugle, J, flag K, and cross-swords L L, the whole being inclosed by scroll-work.

What I claim as my invention, and desire to secure by Letters Patent, is—

The design for the front of a catch-all, as shown, described, and set forth.

JOHN H. BELLAMY.
